HEATING STOVE.

No. 18,831.

Patented Jan. 1, 1889.

UNITED STATES PATENT OFFICE.

OTTO GERMER AND GUSTAVE H. GUENTHIER, OF ERIE, PENNSYLVANIA,
ASSIGNORS TO BLOCK & GERMER, OF SAME PLACE.

DESIGN FOR A HEATING-STOVE.

SPECIFICATION forming part of Design No. 18,831, dated January 1, 1889.

Application filed September 10, 1888. Serial No. 285,081. Term of patent 7 years.

To all whom it may concern:

Be it known that we, OTTO GERMER, a citizen of the United States, and GUSTAVE H. GUENTHIER, a citizen of Germany, residing at Erie, in the county of Erie and State of Pennsylvania, have invented a Design for Heating-Stoves; and we do hereby declare the following to be a full, clear, and exact description of the invention, such as will enable others skilled in the art to which it appertains to make and use the same, reference being had to the accompanying drawings, and to the letters of reference marked thereon, forming part of this specification.

Our invention relates to the form and ornamentation of heating-stoves; and it consists in the features hereinafter set forth, and explained and illustrated by the accompanying photographic views of a stove embodying our design, in which—

Figure 1 is a front elevation of our design for a heating-stove. Fig. 2 is a view in perspective showing one side and the rear of the same.

Like letters refer to like parts in both of the figures.

In its general shape our stove is rectangular, with swell front terminating in a semi-dome-shaped panel under the overhanging molding around the top of the stove.

In its general shape the base A is rectangular, and from its junction with the upright portion of the stove projects outward for a short distance at the front and sides of the stove, forming a narrow hearth, a, and around the outer edge of the front and sides of this hearth is a fine bead molding, a', and from the outer edge of this hearth a the base A curves downward for a short distance somewhat in the shape of an ogee, forming a band, B, entirely around the base A, the lower edge of the band B terminating in a band of shell molding, b. Under the band of shell molding is the curtain consisting of the panels C, occupying the front, the sides, and rear of the stove between the legs E, these panels being ornamented with scroll-work c and central medallions, c', of open-work. Corner panels, D, are formed on the upper portion of the legs E, also ornamented with scroll-work, the

panels C and D being all surrounded and separated by narrow bands or styles d.

The legs E are secured under the corners of the base A, and are ornamented with the corner panels, D, on their upper parts, and below the panels, on their fronts, by foliate work e, and terminate in feet or claws e'. The faces of the front corner-posts, F, of the first section G, above the base A, are ornamented with a base-band, f, of shell-work, and above that with foliate work g, the front of the section G between the posts F being occupied by a door, H, the center of which curves outward to correspond with the contour of the stove front. Across the base of this door H is a band of shell-work ornamentation, h, and above the band h the door H is provided with a window-opening, h', and ornamented with a scroll-work, h'.

The sides of the lower section, G, are ornamented by scroll-work panels I and ornamental brackets J and bars J', the bars J' being ornamented with scroll-work and griffins' heads, the brackets J being ornamented with griffins' heads j and rosettes j'. The rear of the lower section, G, curves outward in the center to accommodate a return-draft flue passing down and up to and from the stove-base A, and is ornamented by a base-band of shell-work, K, above which it is ornamented with corner-post panels k of foliate work, and a central panel, L, surrounded by scroll and foliate work l, and also with panels M on each side of the central panel, L, having central ornaments of scroll-work, m, and between the panels M and the corner panels, k, are plain panels N, divided by transverse bands n.

Above and surrounding the lower section of the stove is an ogee band-mold, O, ornamented around the lower edge by a band of shell ornamentation, o, excepting across the front of the stove, where the shell ornamentation gives place to a panel, P, surrounded by a small bead-mold border, p, said panel P consisting of a name-plate.

The second section, Q, of the front of the stove surmounts the band-mold O, and consists of the corner-posts R and a door, S. The fronts of the posts R are ornamented at their bases by a beaded fluted work, r, and above

the fluted work *r* with foliate work *r'* up to the top of the door *S*, above which an ornamental band, *T*, crosses the entire front of the stove, forming the top of the second section, *Q*, 5 of the stove. The door *S* occupies the entire space between the ornamental corner-posts *R*, and has openings forming two rows of windows, *t t*, divided from each other by rosettes and foliate ornaments *v*, the styles of the same 10 being ornamented by raised borders and rosettes *t'*. Above the band *T* the corner-posts *R* are ornamented with scroll and foliate work 1, surmounted by faces 2 in bas-relief. Between the corner-posts *R*, above the band 15 *T*, is a panel, 3, having a dome-shaped top ornamented with a central medallion, 4, and side medallions, 5, the space in said panel around and between the medallions 4 and 5 being filled with ornamental scroll-work 6, 20 the corners of the front above the dome-shaped panel 3 being filled with ornamental scroll-work 7.

The sides of the second section, *Q*, extend from the band-mold *O* to the under edge of 25 the overhanging stove-top, and are each provided with an outwardly-projecting panel, 8, having an arched or dome-shaped top, 9, the outer faces of these panels being ornamented with scroll-work 10 and a row of rosettes, 11, 30 across the base thereof, the top and sides thereof being surrounded by an ogee molding, 12, ornamented by a band of shell-work, 13. Above the arched tops 9 of the panels 8 and under the overhanging stove-top the space is 35 filled with ornamental scroll-work 14. The rear of the second section, *Q*, of the stove likewise extends from the band-mold *O* to the under edge or the overhanging stove-stop. The rear faces of the corner-posts are ornamented 40 with fluted, foliate, and band work and faces in bas-relief, the same as the front posts heretofore described.

Across the base the rear of the stove above the band-mold *O* is a plain transverse band, 45, above which is a central panel, 16, having an arched top and ornamented with rosettes and foliate work 17, the same as the side panels, 8, and at each side of the central panel, 16, is a narrow vertical panel, 18, filled with scroll 50 and foliate work 19, and the space between the panels 18 and the corner-posts is occupied with plain transverse panels 20, divided from each other by narrow bands 21. It will also be observed that the rear of this section curves 55 outward to accommodate the flue, the same as in the first rear section hereinbefore described.

The top section of the stove consists in an overhanging rim having a plain band, 22, entirely around it. Below the band 22 the top 60 recedes by a gradual curve, 23, until it meets the upright portion of the stove, the curved portion 23 being ornamented with a band of foliate work, 24. Above the band 22 the top curves upward and inward to the base of the 65 second section, 25, of the top, and is ornamented with foliate and rosette work 26. The base of the section 25 of the top is provided

with a narrow plain band, 27, from which it curves upward and inward to the base of the third section, 28, of the top. Above the band 27 is a second band, 30, of shell-work, above this band 30 the front, sides, and rear being ornamented with panels 29, ornamented with foliate work 31, the corner spaces between the panels 29 being occupied by corner panels, 32, 75 ornamented with foliate work 33. The third section, 28, of the cover is provided with a plain band, 34, around its base, from which it curves inward and upward to the base of the urn 35, and is ornamented above the band 34 80 by a band, 36, of fluted work, and at each side of the urn-standard it is provided with open scroll-work 37.

The urn 35 is ornamented by a band of bead-work, 38, around its base, and a band of 85 foliate work, 39, around the body thereof, above which is a border of shell-work, 40, forming an ornamental border around the top thereof. On each side of the urn are ornamental scroll-work handles 41, and centrally 90 from the top of the urn rises an ornately-turned cup, 42, ornamented with foliate work.

Having thus described our new design for heating-stoves, what we claim as new, and desire to secure by Letters Patent of the United States, is—

1. The design for a heating-stove, comprising a rectangular base, *A*, having an ogee-molded and shell-molded edge and a paneled foliate-ornamented curtain, a lower or ash section surmounted by the ogee band-mold *O*, ornamented by the shell molding *o*, and having an outwardly-curving front door, foliate-ornamented front corner-posts *F*, scroll and foliate ornamented end panels, *I*, rear panels, *k N M L*, and the brackets *J*, supporting fender-bars *J'*, an upper or fire section, *Q*, having foliate and scroll ornamented front and rear corner-posts, *R*, surmounted by faces 2 in bas-relief, the outwardly-curving front door, *S*, having open-work windows therein ornamented with scroll and rosette work, the transverse foliate-ornamented band *T* above the door *S*, surmounted by the dome-shaped ornamental panel 3, having medallions 4 and 5 therein, the outwardly-curved panels 8, forming the ends of said section and having dome-shaped tops 9 and ornamented with ogee and shell-band moldings and central scroll-work panels, 10, the plain panels 20, the intermediate panels, 18, ornamented with scroll and foliate work, and the central arched top panel, 16, ornamented with foliate and rosette work, forming the rear of said 110 section, and the top having an overhanging edge, 22, and an outwardly and upwardly curving foliate-ornamented facia, 23, surmounted by an upwardly and inwardly curving foliate and rosette ornamented band, 26, 115 reaching to the base of the second section, 25, of the top, the dome-shaped section 25, ornamented with a plain band, 27, shell-band 30, and foliate-ornamented panels 29 and 32, and 120 125 130

the third section of the top 28 curving upward and inward to the base of the urn 35, ornamented with fluted work 36 and open scroll-work 37, substantially as shown and described.

2. In a design for a heating-stove, a rectangular base, A, having an ogee-molded and shell-mold banded edge and a paneled foliate-ornamented curtain, substantially as shown and described.

3. In a design for a heating-stove, a lower or ash section, G, surmounted by the ogee-band mold O, ornamented by the shell molding o, and having an outwardly-curved front door, foliated-ornamented front corner-posts, F, scroll and foliate ornamented end panels, I, and rear panels, k N M L, the brackets J at the ends of said section ornamented with griffins' heads, and supporting fender-bars J', ornamented with scroll-work, all substantially as shown and described.

4. In a design for a heating-stove, an upper or fire section, Q, having foliate and scroll ornamented front corner-posts, R, surmounted by faces 2 in bas-relief, the front of the lower half of said section between said corner-posts consisting of an outwardly-curved door, S, having open-work windows therein and ornamented with scroll and rosette work, substantially as shown, and the upper half of the front of said section consisting of a transverse foliate-ornamented band, T, above the door S, surmounted by a dome-shaped ornamental panel, 3, having medallions 4 and 5 therein, substantially as shown, and the ends of said section consisting of outwardly-curved panels 8, having dome-shaped tops 9 and ornamented with ogee and shell-band moldings and central scroll-work panels 10, and the rear of said section having ornamental curved corner-posts, substantially as shown, and plain transverse side panels, 20, intermediate panels, 18, ornamented with scroll and foliate work 19, and a central arched top panel, 16, ornamented with foliate and rosette work, all substantially as shown and described.

5. In a design for a heating-stove, the top having an overhanging edge, 22, and outwardly and upwardly curving foliate-ornamented facia, 23, surmounted by an upwardly and inwardly curving foliate and rosette ornamented band, 26, reaching to the base of the second section, 25, of the top, the dome-shaped section of the top 25, ornamented with a plain band, 27, a shell band, 30, and front end and rear panels, 29, ornamented with foliate work 31, and corner panels, 32, ornamented with foliate work 33, and a third section, 28, curving inward and upward from the top of the second section, 25, to the base of the urn 35, and ornamented with fluted work 36 and open scroll-work 37, the whole surmounted by the urn 35, substantially as shown and described.

6. In a design for a heating-stove, the front comprising the door S, having window-openings t t, separated by transverse rosette and foliate ornaments V, and raised borders and rosettes t' on the styles thereof, substantially as shown and described, the band T, ornamented with foliate work above the door S, and the semi-dome-shaped panel 3, having medallions 4 and 5 and ornamented with scroll-work 6, substantially as shown and described, and the scroll ornaments 7, substantially as shown and described.

7. In a design for a heating-stove urn, the semi-globular body 35, having a base with bead-work ornamentation 38, ornamental foliate work 39 around the body thereof, a band 80 of shell-work, 40, forming a border around the top of the urn, the ornamental scroll-work handles 41, and the cup 42, ornamented with foliate work rising from the top of the urn, substantially as shown and described.

In testimony whereof we affix our signatures in presence of two witnesses.

OTTO GERMER.

GUSTAVE H. GUENTHER.
